(57) **CLAIM**

The ornamental design for a top cap for a ladder, as shown and described.

DESCRIPTION

FIG. 1 is a top view of a top cap for ladder showing an embodiment of the design;

FIG. 2 is a perspective view of the top cap shown in FIG. 1; FIG. 3 is a left side view of the top cap shown in FIG. 1; FIG. 4 is a right side view of the top cap shown in FIG. 1; FIG. 5 is a front view of the top cap for ladder shown in FIG. 1; and,

FIG. 6 is a rear view of the top cap for ladder shown in FIG. 1.

The uneven broken line representations in the drawings are for illustrative purposes only and form no part of the claimed design.
